UNITED STATES PATENT OFFICE.

ARTHUR C. DAVIDSON, OF CHICAGO, ILLINOIS, ASSIGNOR TO WAUGH DRAFT GEAR COMPANY, OF CHICAGO, ILLINOIS, A CORPORATION OF ILLINOIS.

DRAW-BAR-CENTERING DEVICE.

1,259,370.

Specification of Letters Patent. Patented Mar. 12, 1918.

Application filed March 22, 1915. Serial No. 16,066.

To all whom it may concern:

Be it known that I, ARTHUR C. DAVIDSON, a citizen of the United States, and a resident of the city of Chicago, in the county of Cook 5 and State of Illinois, have invented certain new and useful Improvements in Draw-Bar-Centering Devices; and I do hereby declare that the following is a full, clear, and exact description of the same, reference being had 10 to the accompanying drawings, and to the numerals of reference marked thereon, which form a part of this specification.

Various devices have been designed with the end in view of maintaining the drawbar 15 and coupler head of a car on which the same are mounted, normally in a central position, so that when the cars are coupled to one another the coupler heads are properly disposed for the purpose. The type of construction used heretofore, although successful in operation, has proved difficult of access, and if for any reason renewal of any 20 of the parts becomes necessary, the dismantling and assembling again of the structure 25 is exceedingly inconvenient and requires considerable time.

It is an object therefore of this invention to construct a centering mechanism for drawbars on cars embracing an easily 30 removable bolt associated with a heavy compression spring acting to control the pivotal movement of a plate which contacts each side of the drawbar to resist movement of the drawbar from a normal central position.

It is also an object of this invention to construct a centering device for drawbars involving the use of a plate capable of movement about either one of two pivot points and between abutments on which the drawbar 40 is adjustably confined with resilient mechanism resisting movement of said plate from a central position stressed in substantially an axial line.

It is furthermore an object of this invention to construct a drawbar centering device 45 wherein the particular form of retaining bolt is such as to permit adaptation thereof to different types of centering devices.

It is finally an object of this invention to 50 improve the construction of drawbar centering mechanisms to facilitate assembly of the parts as well as access thereto for repair or adjustment.

The invention (in a preferred form) is

illustrated in the drawings and hereinafter 55 more fully described.

In the drawings:

Figure 1 is a fragmentary view partly in section and partly in elevation, illustrating a drawbar and coupler mounted on a car 60 with a centering device involving the principles of my invention adapted thereto.

Fig. 2 is a top plan view of the centering mechanism with the operation thereof illustrated in dotted lines. 65

Fig. 3 is a detail section with parts in elevation taken on line 3—3 of Fig. 2.

Fig. 4 is a detail section taken on line 4—4 of Fig. 3, with the retaining bolt omitted. 70

Fig. 5 is a detail section taken on line 5—5 of Fig. 3, with the retaining bolt omitted.

Fig. 6 is a fragmentary front plan view of the supporting bracket plates of the device. 75

Fig. 7 is a bottom plan view of a modified form of device.

Fig. 8 is a fragmentary end view thereof.

Fig. 9 is a section taken on line 9—9 of 80 Fig. 7, with parts shown in elevation.

As shown in the drawings:

Referring to Fig. 1, a car platform is denoted as a whole by the reference numeral 1, being provided as is usual with a tread 85 plate 2, and platform buffer 3, but inasmuch as the operating mechanisms of the latter form no part of this invention, the same have been omitted. The drawbar mounted beneath the car platform and associated 90 with any suitable draft gear (not shown) is indicated by the reference numeral 4, and is provided on its outer end with a coupler head 5. Said drawbar 4, rests upon a flat plate 6, provided with a pair of abutments 95 7, projecting perpendicularly on the upper surface thereof, and the contact surfaces of which for the sides of said drawbar 4, are convex, as clearly shown in Fig. 2. Said plate 6, rests upon a yoked or U-shaped bracket plate or casting 8, which, as clearly shown in Figs. 1 and 2, is suspended upon the frame thereof beneath the car, by means of a U-shaped or yoke bar 9. An upright yoked or U-shaped flange 10, is provided 105 along the rear edge of the supporting bracket 8, and at its extremities, said flange is curved to afford pivot recesses or pockets 11, to re-

ceive therein rounded projections 12, formed on said plate 6, to permit said plate to pivot about either one of said projections in the proper pocket therefor, as clearly shown in 5 dotted lines in Fig. 2.

As illustrated in Fig. 1, a long retaining bolt 13, disposed in horizontal position, extends through an aperture in the downwardly extending flanged portion 10, of the 10 bracket plate 8, and through an aperture in said movable plate 6, said bolt being provided on its end with a cylindrical cross piece 14, which seats in a recess 15, formed in the side of a squared hole 16, extending 15 therethrough. It is particularly in the form and construction of the bolt and the manner of its association with the bracket plate 8, and movable plate 6, wherein my invention lies. Coiled around said retaining bolt 13, 20 is a heavy compression spring 17, one end of which bears against the flanged portion 10, of the bracket 8, and the other end of which bears against a nut 18, threaded on the outer end of the bolt and prevented 25 from becoming loose thereon by a split pin 19, removably engaged therethrough. As clearly shown in Figs. 3, 4, 5, and 6, the opening through the flange of the bracket member 8, is of oblong shape and is indicated by the reference numeral 20, to permit 30 the rounded cross piece or head 14, on said T-head bolt 13, to be projected therethrough and thereafter turned upwardly into a vertical position. The aperture or opening 35 through the bearing portion of the movable plate 6, is also oblong in shape and disposed horizontally, being denoted by the reference numeral 21, as clearly shown in Fig. 4.

In the modified form of device illustrated 40 in Figs. 7, 8, and 9, I have illustrated a yoke or U-shaped fixed bracket plate 22, provided at its inner edge with a downwardly extending flange 23, and with an integral cross brace member 24, extending between the 45 arms of the U so formed. As in the previous construction, a plate member 25, provided with rounded pivot bearing extensions 26, rests upon the upper surface of the bracket plate 22, with the pivot extensions seated in bearing recesses formed by upwardly curved projecting flanges 27, on the upper surface of the bracket plate 22. As before, convex abutments 28, are provided on the upper surface of the movable 55 plate 25, between which the drawbar of the car is disposed and against which the same is adapted to bear in swinging from side to side. For the purpose of normally maintaining said plate 25, in central position, a retaining T-headed bolt 29, is provided, the T-head of which consists of a cylindrical cross piece 30, which normally rests in a vertical bearing recess formed between the ribs 31, on the outer side of the downwardly directed flange 23, of the bracket plate. 60

Coiled about said bolt 29, is a heavy compression spring 32, which at one of its ends bears against a nut 33, threaded on the end of said bolt and locked thereon by a pin 34, and at its other end bearing against a downwardly flanged shoulder 35, formed integral with the under side of said plate 25, and through which said bolt 29, extends. A supporting member, denoted by the reference numeral 36, is provided for said stationary 75 U-bracket 22, being secured thereto by means of bolts 37.

The operation is as follows:

In the form of device illustrated in Figs. 1 to 6 inclusive, the stress of the spring 17, 80 acts normally to resist pivotal movement of the plate 6, upon the bracket member 8, so that a drawbar disposed between the abutments 7, on said plate 6, when swung from a central position, unless positively held in 85 such a position, will be returned by the plate 6, under the stress of the compression spring 17. The plate 6, in its pivotal movement on the bracket member 8, pivots upon either one of the rounded members 12, as the 90 case may be, so that the movement of the bolt 13, which is drawn inwardly when the movable plate 6, is swung into a position to one side, is practically along a straight line, and direct compression of the spring 17, 95 results. In assembling the device the rounded cylindrical cross member 14, on said bolt 13, is first inserted through the horizontal slots in the flange 10, of the bracket 8, and the corresponding registering slots 100 provided in a downwardly flanged extension of the movable plate 6, and thereafter is rotated to dispose the cylindrical member 14, into a vertical position to seat in the rounded recess 15, provided therefor 105 in the squared aperture 16, which is provided in said movable plate 6. The coiled spring 17, is then inserted over the bolt, and the lock nut 18, threaded thereon, after which the cotter pin 19, is inserted therethrough to prevent loosening of the nut. 110

In the form of device illustrated in Figs. 7, 8, and 9, the retaining bolt, being denoted by the reference numeral 29, is disposed in a different position to make the device as 115 a whole more compact, but the operation of the movable plate in the first instance, denoted by the reference numeral 25, is identical. In the latter construction a cylindrical cross member 30, is provided on 120 the end of the bolt as before, but it is not necessary to provide horizontally disposed oblong slots for insertion of said cross member therethrough in putting the bolt 29, in place, for the reason that the bolt is inserted 125 threaded end first through the respective registered apertures in the bracket member and flange of the movable plate.

I am aware that various details of construction may be varied through a wide 130

range without departing from the principles of this invention, and I therefore do not purpose limiting the patent granted otherwise than necessitated by the prior art.

5 I claim as my invention:

1. In a device of the class described, a stationary member, a movable plate member adapted for pivotal movement thereon, abutments on said plate member adapted to project on each side of the drawbar of a car, an integral one piece T-headed bolt extending through registering apertures in said members, and a spring coiled thereabout to resist movement of said movable member from a central position, said bolt and spring adapted to be simultaneously removed from engagement with said members by simply compressing the spring and turning the bolt.

10 2. In a device of the class described, a stationary member, a movable member mounted thereon, a plurality of pivot points for movement of said movable member with respect to said stationary member, downwardly projecting means on each of said members, a T-headed bolt extending through registering apertures in said respective means, and a spring coiled thereabout to resist relative movement between said members, said T-headed bolt and spring adapted to be removed from the device by rotating said T-headed bolt ninety degrees to permit the same to be drawn outwardly through said apertures.

15 3. In a device of the class described, a stationary member having a recess therein, a movable member disposed thereon adapted for pivotal movement at different pivot points thereon, abutments on said movable member adapted to project on each side of the draw-bar of a car, and means positioned

below said member and seated in said recess acting to resist movement of said movable member about a pivot point from a central position with respect to said stationary member, said means adapted to be removed from its seated engagement with said recessed stationary member by simply rotating the same.

4. In a device of the class described the combination with a drawbar of a car, a stationary plate thereon having a vertical recess and a horizontal slot therein, a movable plate pivotally mounted on said stationary plate having a horizontal slot therein adapted to register with the slot of said stationary plate, resilient means for resisting movement between said plates, and headed means engaging the same adapted to be removably inserted through said registering slots and rotated through an angle of ninety degrees to seat in said recess to removably hold said resilient means in position.

5. A centering device for couplers comprising a stationary member, a movable member, abutments on the movable member, said members having registering elongated slots, and one member having an elongated recess extending transversely of the slots, a retaining member having an elongated head adapted for insertion through said elongated slots and after insertion being turned for the head to engage in the recess and a tension spring on the retaining member.

In testimony whereof I have hereunto subscribed my name in the presence of two witnesses.
